ASH SIFTER

William E. Althaus and Russell C. Swank, Dayton,
Ohio

Application March 18, 1932, Serial No. 599,704

4 Claims. (Cl. 209—377)

This invention relates to ash sifters for furnaces and one object of the invention is to provide means whereby ashes may be sifted in the ash pit of the furnace, thereby confining the dust to the ash pit and avoiding unnecessary handling of the ashes.

A further object of the invention is to provide an ash sifter constructed separately from the furnace and adapted to be inserted in and supported within an ash pit in a position to receive the ashes as they drop from the grate.

A further object of the invention is to provide an ash sifter of this type which will be simple in its construction, inexpensive to produce and which can be easily inserted in the ash pit and operated therein.

Other objects of the invention will appear as the device is described in detail.

In the accompanying drawings Fig. 1 is a plan view; partly broken away, of an ash sifter embodying our invention showing the same within the ash pit; Fig. 2 is a transverse sectional view taken on the line 2—2 of Fig. 1; Fig. 3 is a plan view of the supporting frame showing the same partially collapsed; Fig. 4 is a detail view of a portion of the screen; Fig. 5 is an end elevation of a portion of an ash sifter showing a slightly modified form of supporting frame; and Fig. 6 is a detail view of a portion of one of the inclined guide plates showing a slight modification thereof.

In these drawings we have illustrated one embodiment of our invention with certain minor modifications thereof but it will be understood that these have been chosen for the purpose of illustration only and that the apparatus may take various forms without departing from the spirit of the invention.

In carrying out our invention we mount a suitable screen within the ash pit of the furnace, in a position to receive the ashes which drop from the grate, and support this screen in such a manner that it may be vibrated to separate the ashes from the partially burned coal and may be removed from the ash pit for the purpose of discharging therefrom the partially burned coal which has accumulated therein. The screen may be mounted in various ways but when the ash pit of the furnace is not so constructed as to provide a support for the screen it is necessary to provide a supporting structure which may be inserted in the ash pit and on which the screen may be movably supported.

In Figs. 1, 2 and 3 we have shown an ash sifter constructed as a complete unit separate from the

furnace and adapted to be inserted in the ash pit of the furnace. The supporting structure or frame comprises upright side members 10 which are connected one to the other and are provided with means for supporting the screen, which is here shown as a shallow receptacle or pan 11 having a foraminous bottom 12. The side members 10 may take various forms and, as shown in Figs. 1 and 2, each side member is formed from a single sheet of metal having its lower portion bent inwardly, as shown at 13, and having its upper portion bent outwardly to form a shoulder 14, which constitutes a guide, and then extended upwardly and again bent outwardly to form a flange 15. Between the shoulder 14 and the lower edge of the side member the latter is bent outwardly to provide a second shoulder 16 which also constitutes a guide. The screen, which is arranged between the side members, is provided with suitable means for slidably supporting the same upon the guides carried by the side members and when these guides are in the form of shoulders, as here shown, we prefer to provide the screen at its upper edges with outwardly extending flanges 17 which are slidably supported upon the respective shoulders or guides. The screen may be provided at its forward end with an inclined portion 18 to facilitate dumping the coal therefrom and, as here shown, this inclined portion has a downturned flange 19 forming a hand grip which may be grasped to impart vibratory movement to the screen on the guides, or to remove the screen from the supporting structure when its contents are to be dumped.

It is also desirable, although not necessary, to provide an ash pan to receive the ashes from the screen and we have shown such an ash pan at 20 and it is provided at its upper edges with laterally extending flanges 21 to engage the lower shoulders 16 on the side members. When the ash pan is not employed the lower guides or shoulders may be omitted. If desired, the front end wall of the ash pan may be omitted and the side walls braced by a cross bar 22.

The doorways of ash pits are often of a width less than the width of the ash pit and the supporting frame for the ash sifter may therefore sometimes be of greater width than the door. To enable the frame to be inserted through such a narrow doorway we have made the same collapsible so that the two side members can be moved one toward the other to permit the frame to be inserted in the ash pit and then extended to their normal positions. As here shown, the lower portions of the side members are connected

one to the other by cross bars 23 and the upper portions of the side members are connected by cross bars 24, the several cross bars being pivotally connected with the respective side members so that the side members may be moved one toward the other, as shown in Fig. 3.

The walls of an ash pit are usually curved so that it is not practicable to make the supporting structure of a width equal to the greatest width of the ash pit and in order that all the ashes dropping from the grate may be directed onto the screen we have provided guide plates or chutes which extend laterally from the respective sides of the screen and which are adapted to receive ashes and guide the same onto the screen. These guide plates may be of any suitable character and may be supported in any desired manner. As here shown, each side plate comprises two fins, 25 and 26, extending lengthwise of the frame. Each inner fin 25 is provided with slots 27 and is connected with a flange 15 of the frame by bolts 28 extending through the slots and through the flange. The outer fin 26 is also provided with slots 29 and is connected with the inner fin by bolts 30 extending through the slots and through the outer portion of the inner fin. In the present drawings the ash pit is shown as curved at its rear end only, the front portions of its side walls being parallel. Consequently the rear portions of the fins are curved and the slots are inclined so that the fins will be moved into engagement with the wall, after which they are secured in position by tightening down the bolts. Where the walls of the ash pit are of different shape the fins may be given a different shape or extension plates may be provided for attachment to the fins, as shown at 31, in Fig. 6, to adapt them to the contour of the ash pit wall. We have also shown the screen as provided at its rear end with a guide plate or chute 32 which abuts against the curved rear wall of the ash pit. In order to hold the frame members against relative movement after they have been extended within the ash pit we have provided locking members adapted to be moved into engagement with an adjacent portion of the ash pit wall and secured in engagement therewith. In the present construction these locking members are in the form of slotted bars 33 which are adjustably mounted on the slide plates and adapted to be moved into engagement with the front wall of the ash pit and held in that position by bolts 34, thus holding the fins in engagement with the walls and holding the frame members to which the fins are secured against movement.

As has been stated, the supporting structure may take various forms and in Fig. 5 we have shown a frame in which each side member comprises a plurality of uprights 35 connected one to the other by a longitudinal plate 36 which is rigidly secured thereto and which has its upper and lower edges bent inwardly, as shown at 37 and 38, to provide the guides for the screen and the ash pan. A separate plate 39 may be secured to the uprights and have its upper edge bent outwardly, as shown at 40, to support the guide plate or chute. The upper and lower por-

tions of the uprights 35 are bent inwardly, as shown at 41 and 42, and pivotally connected with the cross bars 43 and 44.

While we have shown and described one embodiment of our invention, with certain modifications thereof, we do not desire to be limited to the details thereof as various modifications may occur to a person skilled in the art.

Having now fully described our invention what we claim as new and desire to secure by Letters Patent, is:

1. In an ash sifter for a furnace, a frame adapted to be inserted in the ash pit of the furnace and comprising side members having guides extending lengthwise thereof, cross members pivotally attached to the respective side members to collapsibly connect the same, and a screen arranged between said side members and having parts engaging said guides to slidably and removably support said screen thereon.

2. In an ash sifter for a furnace, a frame adapted to be inserted in the ash pit of the furnace and comprising side members having guides extending lengthwise thereof, cross members pivotally attached to the respective side members to collapsibly connect the same, a screen arranged between said side members and having parts engaging said guides to slidably and removably support said screen thereon, and laterally extending guide plates carried by the respective side members and adjustable with relation thereto to position the outer edges of said guide plates close to the walls of said ash pit when said frame is in its extended position.

3. In an ash sifter for a furnace, a frame adapted to be inserted in the ash pit of the furnace and comprising side members connected one to the other in spaced relation, each side member comprising a plate of sheet metal having portions bent laterally to form upper and lower longitudinal guides, a screen arranged between said side members and slidably and removably supported on said upper guides, an ash pan removably supported on said lower guides, and guide plates mounted on the upper portions of the respective side members for longitudinal and lateral adjustment with relation thereto.

4. In an ash sifter for a furnace, a frame adapted to be inserted in the ash pit of a furnace and comprising side members each formed from a plate of sheet metal having intermediate portions bent outwardly to form a longitudinal channel and having its upper portion bent outwardly and then upwardly to form a shoulder, and laterally extending guide plates secured to the upper portion of each side plate, means for connecting said side members for movement one toward the other, whereby said frame may be collapsed, a screen arranged between said side members and having flanges slidably supported on the shoulders of said side members, and an ash pan arranged between said side members and having flanges slidably supported in the channels of said side members.
